[57] CLAIM

The ornamental designs for a disc holder, as shown and described.

DESCRIPTION

FIG. 1 is a front perspective view of a disc holder showing my new design;
 FIG. 2 is a front elevational view thereof;
 FIG. 3 is a left side elevational view thereof, the right side being a mirror image;
 FIG. 4 is a rear elevational view thereof;
 FIG. 5 is a top plan view thereof;
 FIG. 6 is another front perspective view showing the cover in open position;
 FIG. 7 is another front perspective view showing the disc holder in operating order; and,
 FIG. 8 is a bottom plan view thereof.
 The broken lines in FIG. 7 are for purposes of illustration only and form not part of the claimed design. The solid black in FIGS. 1, 2, 5, 6, 7 and 8 is included to disclose that the disc cradles in the claimed design are alternating colors.
